SYNCHRONIZING SYSTEM

William K. Sonnemann, Dallas, Tex., assignor
to Westinghouse Electric & Manufacturing
Company, a corporation of Pennsylvania

Application July 23, 1931, Serial No. 552,673

9 Claims. (Cl. 171—118)

The present invention relates to means for synchronizing a plurality of alternating-current electrical power circuits.

The increasing demand for better efficiency and continuity of alternating-current power service has resulted in rapid development of existing and contemplated power and network systems. Greater continuity of service has been obtained by providing a plurality of independent power sources for loop or ring systems and network loads. In this manner the continuity of power supply is limited only by the reliability of the prime mover at the several sources.

The supply of power from different sources necessitates a synchronizing function and, to insure increased efficiency, the synchronizing must be effected automatically. The usual automatic-synchronizer serves to connect two power systems when the respective voltages are of the same magnitude, in phase, and of the same frequency. This synchronizer takes into consideration the operating characteristics of the associated circuit breaker so as to insure the closure of the circuit-breaker contacts only when the above conditions exist. This known synchronizing arrangement is admirably adapted to all systems of paralleling and interconnecting of independent systems, and is more desirable, and in the majority of systems, necessary over a manually-operable scheme.

The known automatic-synchronizing systems, although they effect the desired synchronizing function, are quite expensive and require extreme accuracy in design and manufacture. It becomes apparent, therefore, that, with the newer and expanding power systems, the demand for some type of automatic synchronizing arrangement is materially increased, with the result that the expense of a suitable synchronizing device becomes an important factor.

It is an object of the present invention, therefore, to provide a simplified means for verifying conditions of synchronization in an electrical system.

Another object of the present invention is to provide a means for verifying conditions of synchronization between two alternating-current sources, within a predetermined range of electrical conditions.

Another object of the present invention is to effect the automatic closing of a circuit breaker connected between an energized system and a de-energized system.

Another object of the present invention is to effect the electrical connection of two alternating-current systems, only when the magnitude,

phase position, and frequency of the two system voltages bear a predetermined relation.

A further object of the present invention is to effect the electrical connection of two alternating-current systems only when the difference voltage between the two systems falls within a predetermined range of phase difference with respect to one of said system voltages.

A further object of the present invention is to provide a means for substantially verifying the condition of synchronization between two alternating-current systems and for modifying the range of verification in accordance with the magnitudes of the respective system voltages.

Further objects and advantages of the present invention will become apparent from the following detailed description of the several figures in the drawings.

It should be noted that the present invention is not proposed as a substitute for the known synchronizing arrangements in all synchronizing applications. For instance, in systems requiring the connecting of two power systems only when the respective voltages are exactly equal in magnitude, phase position and frequency, the present invention will not apply and it will be necessary to employ the more expensive and complicated known synchronizing arrangements. These arrangements have the feature of closing ahead of synchronism at an angle of phase advance proportional to the beat frequencies and determined by the speed of operation of the circuit breaker so that the two systems are connected exactly on synchronism. The present invention does not have this feature.

The application of the present invention is quite extensive in view of the nature of many power systems, as mentioned hereinbefore. One application exists in ring or loop systems where the loads are supplied from more than one generating station and for some reason one section of the loop has been taken out of service. Obviously there is no danger in reconnecting one end of the section by any suitable circuit-breaker reclosing system, but the other end of the isolated section cannot be reconnected unless the magnitude, phase position and frequency of the two system voltages are substantially the same. If the other tie or ties between the several power sources remain connected, the voltages on the two sides of the open breaker will necessarily be substantially the same in magnitude and phase position as well as in frequency, and the present invention serves to check or verify the existence of such conditions before reclosing the circuit.

breaker. In such applications, it is obvious that a means of exactly checking synchronism is not imperative and the simple inexpensive synchronizing system of the present invention may be utilized in preference to the more costly and complicated automatic synchronizer used heretofore.

The present synchronizing arrangement may also be adapted to sectionalized power transmission lines, particularly if the lines are extensive and offer substantial impedance to the flow of circulating currents. The present arrangement will not effect the connection of two independent systems when an appreciable beat frequency exists, and adjustments are provided to control the magnitude of the beat frequency for which the invention will operate to effect the connection of the systems. The higher the phase difference for which the device operates, the greater is the beat frequency for which operation is possible. The operation of the present device with reference to the permissible beat frequency will be described in detail hereafter.

The novel design of the present invention affords a large application in network systems where it is mandatory that power flow is from a feeder circuit to a network load. The importance of this application may best be realized by the central station operator who is now required to utilize a complicated relay arrangement for insuring the flow of power to a network load. The applicability of the present invention to network systems will readily become apparent from a study of the novel means of altering the characteristics of the proposed synchronizing arrangement.

Since the present invention does not provide automatic synchronization in the accepted usage of the term, but merely verifies the condition of synchronization, the term synchro-verifier will be used in the following description.

The synchro-verifier operates on the induction principle, similar to an induction disc wattmeter, and comprises two electro-magnet elements adapted to effect the rotation of suitable disc elements for actuating a set of contacts. The two electro-magnet elements are positioned in vertical alignment and the two disc elements are adapted to rotate the same spindle or shaft and the contact means associated therewith. The electro-magnet elements are of substantially the usual construction with an important exception, the nature and purpose of which will be fully explained later. These elements embody the usual upper and lower pole portions, adapted for the reception of suitable flux producing windings, and the torque, resulting from the interaction of the pole fluxes of the respective electro-magnet elements, effects a resulting rotation or turning torque to actuate the single contact spindle.

The function of the synchro-verifier being to permit the connection of two independent systems or bus sections within predetermined limits of electrical conditions, it is necessary to compare the respective voltages in some suitable manner. For this purpose voltage transformers may be employed or the charging current of the condenser or oil-filled bushings on the circuit breaker may be utilized, together with any necessary phase-angle or power-factor correcting network. For present purposes, the application of the synchro-verifier will be described with reference to voltage-transformer energizing means.

The upper and lower electro-magnet elements will be referred to as element A and element B,

respectively, in order to facilitate the understanding of and reference to the function of the synchro-verifier. The lower coil winding of element A is energized directly in accordance with the voltage on one side of the open circuit breaker while the lower coil winding of element B is energized in accordance with the voltage on the other side of the open breaker. The reference to the synchro-verifier in combination with a circuit breaker, throughout the specification, includes the application of the present invention for verifying the conditions of synchronization between two systems or busses connected to the respective terminals of any suitable circuit breaker.

The upper coil windings of elements A and B are connected in parallel and energized in accordance with the difference voltage between the two systems, and may be referred to as phasing windings. The lower coil winding, or voltage winding of element A, is adapted to produce an alternating-current flux which combines with the flux produced by the phasing winding of that element to effect a rotating torque acting upon the associated disc element to rotate the contact spindle in an assumed positive direction. For the same two system voltages the voltage and phasing windings of element B are arranged to effect a rotating torque acting upon the disc element of element B in an opposed or negative direction. Thus, assuming the two systems to be in energized condition, the elements A and B exert opposing torques and the single contact spindle is rotated in accordance with the resultant torque developed by the two elements. The assumed positive direction is that of contact closing while the opposed or negative direction relates to a torque acting to open the contacts.

Under most system conditions, the two electrical torques are opposed, that is, when one element is exerting a positive torque, the other element is exerting a negative torque. However, under some conditions this torque relation is not strictly true. One such condition may exist when the difference or phasing voltage leads or lags the potential coil voltage of one element by an angle greater than 90°, and the difference voltage impressed upon the phasing coil windings of the other element leads or lags the potential coil voltage impressed on that element by an angle less than 90°. Under this condition, the two elements effect torques in the same direction, the direction and magnitude of such resulting torque depending upon the particular electrical energizing conditions and range of phase angle for which the synchro-verifier is adjusted. The nature of the electrical torques which may be obtained in the synchro-verifier will be treated in more detail hereafter.

In order to better understand a form of construction and the function and operation of the present invention, reference will be made to the several drawings wherein,

Figure 1 is a view, in front elevation, of a preferred embodiment of the present invention,

Fig. 2 is a view in side elevation, partly in section, taken on the line II—II of Fig. 1,

Fig. 3 is a schematic diagram illustrating the wiring connections of the synchro-verifier,

Fig. 4 is a vector diagram representing several possible voltage conditions with one adjustment of the synchro-verifier,

Fig. 5 shows the general vector relation existing between the two system voltages as applied to the synchro-verifier,

Figs. 6 to 11, inclusive, are diagrams illustrating the vector relation between the respective

voltages for different possible settings and characteristics of the synchro-verifier.

Fig. 12 is a schematic wiring diagram of a simple application of the present invention for verifying conditions of synchronization between two energized systems, and

Fig. 13 is a schematic wiring diagram of the present invention in combination with suitable relay means for effecting the connection of any two systems under predetermined electrical conditions.

Referring more particularly to Figs. 1, 2 and 3, and bearing in mind that Fig. 3 is merely a schematic illustration of the wiring connections of the synchro-verifier, a practical embodiment of the present invention comprises a base portion 1 for housing the elements A and B of the synchro-verifier. As stated hereinbefore, the mechanical structure of the two elements is substantially the same, the iron laminations and windings being assembled upon a movement frame 2 by means of screws or bolts 3 and the movement frame assembly fastened to raised portions 4 of the base portion 1 by means of screws 6. The elements A and B are comprised of iron laminations 7 having upper poles 8, lower poles 9, phasing windings 11, voltage windings 12 and disc elements 13.

The iron laminations 7 are in two portions, the laminations comprising the upper poles 8 being dove-tailed with the laminations comprising the lower pole portions 9. In an ordinary electro-magnet element, such as provided in a wattmeter, the laminations comprising the upper and lower pole portions are secured firmly as a unit. However, in the present invention, the lower pole laminations are secured together by machine screws 14, nuts 16 and washers 17, and the upper pole laminations are firmly secured by front plate members 18, rear plate members 19 and machine screws 21.

The movement frame 2 is shown partly in section at 22 (Fig. 2) in order to more clearly indicate the relation between the front plate members 18 and elliptical holes 23 in the movement frame. The front plate members 18 are provided with slots or holes 24 adapted for the reception of any suitable prying or moving means which may be inserted through the holes 23 for the purpose of moving the upper pole laminations with respect to the lower pole laminations. The provision of this adjustable feature permits desired characteristics to be imparted to the syncro-verifier, either at the time of assembly in the factory or in the field application.

A spindle or shaft 26 is associated with the two disc members 13 by usual clamping means 27 and is adapted to rotate in a suitable lower bearing structure 28. The upper bearing, not shown in the figure, is of the pin type. It will be observed that the spindle 26 is so aligned with respect to the movement frame 2 that only small portions of the discs 13 rotate between the poles of the respective electro-magnet elements.

Non-magnetic lag plates 29, such as copper, are provided for elements A and B and are adapted to lag the flux of the main pole or voltage windings 12. The lag plates are carried by L-shaped brackets 31 which may be secured to the movement frame 2 by means of screws 32 and spring washers 33. The brackets 31 are provided with slots 34 for the reception of the screws 32 and the lag plate assemblies are adapted to be moved laterally with respect to the pole 9 by means of vernier screws 36. Guide members 37, integral with the movement frame 2, are provided

for the reception of the screws 36. By turning the vernier screws 36, the amount of flux lag and, therefore, the torque characteristics of either or both of the elements A and B may be adjusted as desired. It is unnecessary to loosen the screws 32 in making this adjustment.

A permanent magnet 38 is associated with the disc element 13 of the electro-magnet element A and provides a damping characteristic in the direction of disc rotation. This magnet, as is usual in damping magnets, comprises two permanent magnets positioned in opposed polarity and clamped together by means of front and back plate members 39 and countersunk screws 41. The back plate members 39 are adjustably positioned on the movement frame 2 by means of slots 42 and holding screws 43.

The damping effect of the magnet 38 may, therefore, be modified by loosening the holding screws 43 and moving the magnet assembly laterally with respect to the disc 13.

A bearing bracket 44, of substantially U-shape, is secured to the upper portion of the movement frame 2 by screws 46 and supports a countershaft 48 and gear 52. The countershaft 48 is positioned between the U arms of bracket 44 by means of lower and upper bearing structures 49 and 51 respectively, and a gear 52 is associated therewith and meshes with the pinion 47 on the shaft 26.

The counter-shaft 48 is covered with a moulded insulation hub 53, around which the moving contact arm 54 is clamped by means of a screw 56. A suitable contact, preferably silver, is secured to the contact arm 54, as shown at 57. An L-shaped spring-adjusting bracket 58 is secured to the bracket member 44, but removed therefrom by an insulation block 59, by means of screws 60. One of the screws 60 serves as a clamping means for an electrical conductor 61. The spring adjusting bracket 58 is adapted to adjustably hold a spring adjusting hub and plate member 62 by means of screws 63 and lock washers 64. The member 62 is fitted around the insulation hub 53 and permits the free rotation of the hub and of the counter-shaft 48. A vertical portion 66 of plate 62 is secured to the outer end of a spiral spring 67, the inner end of the spiral spring being secured to a projection of the contact arm 54, not shown. An electrical connection is thus effected between the plate 62 and spring 67, and also between the spring 67 and the moving contact arm 54.

In accordance with the above detailed construction, the tension of the spiral spring 67 may be modified as desired by loosening screws 63 and moving the hub and plate member 62. Obviously the tension on the spring may be made either positive or negative, depending upon the operating characteristics required.

A stationary contact 68 is secured to an insulating block 69 by screws 70 and the block 69 is, in turn, secured to the movement frame 2 by screws 72. One of the screws 70 is utilized to clamp an electrical conductor 71 and, when the contacts 57 and 68 are closed, an electrical connection is provided between 61 and 71.

When the spiral spring 67 is given an initial positive tension, the contacts 57 and 68 are in closed position, and the value of such tension may be changed as indicated above. If the spiral spring 67 is given an initial negative tension, the contacts 57 and 68 are in open position and the tension in this direction may be modified at will.

A stop member 73 is secured to the disc element 13 of element B and permits approximately 195° of rotation.

rotation of the discs and prevents injury of the contacts 57 and 68.

Terminals 76, 77, 78, 79, 81, 82 and 83 are provided for effecting the proper electrical connections in and to the synchro-verifier, and the terminals are secured to the base portion 1 by insulators 84 and screws 86. Contact screws 87 are provided for clamping the respective electrical conductors associated with the terminals, and a grounding terminal 88 is secured to the base 1.

Stud members 91 are secured to raised portions 92 in the base 1 and are adapted to receive and hold in position a glass cover 93 by means of cooperating thumb nuts 94. A gasket or washer 96 of any suitable material, such as felt or cork, is placed between the cover 93 and the base 1 and affords a dust-proof and resilient connection.

In order to better understand the function of the synchro-verifier for the different possible synchronizer or relay characteristics, it will be assumed that the voltage coil 12 of element A is energized in accordance with one system voltage, the voltage coil 12 of element B is energized in accordance with the voltage of a second system, and the phasing coils 11, of both elements, are connected in parallel and energized in accordance with the difference voltage existing between the two systems.

For ordinary synchronizing purposes, the torques developed by elements A and B, under the same electrical energizing conditions, are made equal and opposed. Obviously, if the voltages of the two systems are equal, in phase and of the same frequency, the phasing coils 11 are not energized and there is no torque effected by either element unless the over-voltage adjusters or copper lag plates are moved to one side or the other. The provision of the over-voltage adjusters permits the imparting of any desired torque characteristic to its associated element, the resultant direction of such torque depending upon the direction of movement of the lag plate. This torque results when only the voltage coil is energized, and an important application of the present invention is made possible by reason of this feature. This application relates to alternating-current network systems and will be considered in detail hereinafter.

Another important adjustment is provided in the means for moving the upper pole laminations with respect to the lower pole laminations of each element. The torque developed by one element may thus be varied relative to the torque developed by the other element and this adjustment permits the accurate balancing of the torques of the two elements when both are energized under the same electrical conditions. This adjustment is usually made at the time of manufacture of the synchro-verifier, but obviously, in view of the adjustment described hereinbefore, the characteristics of the present invention may be altered as desired by the user in the field.

The potential coils 12 of elements A and B are so designed that the main pole flux lags the impressed voltage by approximately 90° and the phasing coils are so designed that the phasing coil fluxes are substantially in phase with the phasing coil voltages, with the result that each electro-magnet element has watt characteristics, that is, zero torque is produced on either element when the voltage impressed across the phasing circuit of that element leads or lags the voltage impressed across the voltage coil of that element by 90°. A schematic representation of means for lagging the pole flux effected by the

voltage windings 12 is shown in Fig. 3, wherein short-circuited turns of conducting wire 15 are placed around the upper portion of poles 9. In the following description of the electrical characteristics of the present invention, the electro-magnet elements of the synchro-verifier will be presumed to have substantially watt characteristics.

One object of the present invention being to effect the connection of two energized systems within a predetermined range of electrical conditions, reference will be made to the vector representation of Fig. 4 for purposes of explanation.

All of the torques acting to close or maintain the synchro-verifier contacts closed will be considered positive and all contact opening torques will be considered negative. Assuming the respective torques of the two elements to be equal and opposed under the same electrical energizing conditions, and no electrical torques produced when only the voltage coils are energized, an explanation of the principles upon which the synchro-verifier operates when the spiral spring is exerting a positive torque will be considered.

In the vector diagram of Fig. 4, E_1 represents the voltage on one side of an open circuit breaker, E_2 represents the voltage on the other side of the circuit breaker and E_3 represents the voltage across the open circuit breaker or the difference between the voltages E_1 and E_2 . Assuming the voltage E_2 to be equal to and in phase with the voltage E_1 , the difference voltage E_3 is zero and the electrical torque developed will be zero for each element, thereby resulting in the relay contacts being closed because of the initial tension on the spiral control spring.

Now assuming the voltage E_1 to remain constant and that the voltage E_2 increases along the line OD, an electrical torque will be produced and, with the voltage coils of the elements A and B energized in accordance with the voltages E_1 and E_2 , respectively, element A will produce a contact closing torque and element B will produce a contact opening torque.

In view of the watt characteristics of the two elements, the closing torque developed by element A will be proportional to E_1 times E_3 times the cosine of the angle between them, while the contact opening torque developed by element B will be E_2 times E_3 times the cosine of the angle between them. Thus it may be seen that the contact closing, or positive, torque of element A is increasing as E_3 increases, but the negative torque developed by element B is also increasing and at a faster rate due to the fact that not only is E_3 increasing but E_2 is increasing and the angle between E_2 and E_3 is becoming smaller.

It follows, therefore, that the resultant electrical torque is becoming more and more negative as the voltage E_2 increases along the line OD until some point, such as point L, is reached. At point L, the resultant negative electrical torque just balances the positive torque of the spiral control spring and for any further increase in E_2 beyond the point L, the resultant electrical torque developed will be greater than the torque developed by the spiral control spring and the contacts will be positively held open by a torque equal to the resultant electrical torque minus the torque of the spiral control spring.

Next assume the voltage E_2 to again be equal to and in phase with the voltage E_1 and decreasing along the line OC. The torque developed by element A is now negative and is increasing as E_3 increases. The torque produced by element

B is positive and is increasing as E_3 , decreasing as E_2 and decreasing further in value because of the increase in the angle between E_2 and E_3 . Obviously the positive torque produced by element B will increase at first, but it will not increase as fast as the negative torque produced by element A so that when a point, as point M, is reached, the resultant electrical torque will just equal the torque of the spiral control spring and any further decrease in the voltage E_2 , past the point M, effects a resulting negative electrical torque which is greater than the torque of the spiral control spring and provides a resultant contact opening torque.

15 In a similar manner, the torque characteristics may be determined when the voltage E_2 is increasing along the line OF or decreasing along the line OG. Assuming the voltage E_2 to be increasing along the line OF, the element A effects a positive torque which is increasing as E_3 increases. At the same time element B is producing a negative torque, which increases as E_2 and E_3 increase, and also because of the decrease in the angle between E_2 and E_3 . At a point N, the resultant electrical torque and the torque of the spiral control spring are equal and the further increase of the voltage E_2 effects a resulting contact opening torque. Conversely, when the voltage E_2 is decreasing along the line OG, the negative torque produced by element A is increasing at a faster rate than the increase in positive torque produced by element B, with the result that at a point P, the resultant electrical torque is equal to the torque developed by the spiral control spring. Further decrease of the voltage E_2 effects a resultant contact opening torque.

It may be shown that the torque balance points L, M, N, and P fall on the circumference of a circle having its center at O. Thus, for any given initial positive tension on the spiral control spring, the locus of all of the points at which the resultant electrical torque just balances the torque of the spiral control spring is a circle 40 with its center at O, labeled "Operating curve".

The following mathematical derivation of the relay characteristics should aid in the understanding and application of the synchro-verifier or relay.

50 The several contact-closing torques may result either from the torque effected by the initial tension imparted to the spiral control spring, or by the torques produced by the electro-magnet elements A and B. The torques produced by the two elements A and B in turn result from the usual torque developed by the interaction of the fluxes of the respective voltage and phasing windings or by adjustment of the copper lag plate or over-voltage adjuster associated with each element.

Reference will be made to the vector diagram of Fig. 5, wherein any assumed relation may exist between the voltages E_1 and E_2 . Again E_1 is considered as the reference voltage and the voltage E_2 is represented as leading the voltage E_1 by an angle β . The angle between the voltage E_1 and the phasing or difference voltage E_3 is represented by the angle θ , and the angle between the voltage E_2 and the difference voltage 65 E_3 is represented by the angle ϕ . In other words, in the vector diagram of Fig. 5, the voltage E_3 leads the voltages E_1 and E_2 by the angles θ and ϕ , respectively.

Inasmuch as the respective fluxes produced by 75 the voltages E_1 and E_2 lag the impressed voltages

by an angle of substantially 90° , and the fluxes produced by the voltage E_3 are substantially in phase with the voltage E_3 , the maximum torque line for each element should lie substantially along the vectors E_1 and E_2 . To consider a more general case, the fluxes produced by the respective voltages E_1 and E_2 will be assumed to lag by an angle of $90^\circ - \alpha$. Since the maximum torque is provided when the fluxes produced by the respective phasing and voltage windings are in phase, it follows that when the difference voltage E_3 leads either the voltage E_1 or E_2 by the angle α , the torque produced by the particular energized element will be at a maximum. The maximum torque line for element A is, therefore, indicated by line AA' and leads the voltage E_1 by the angle α . Similarly, the maximum torque line for element B is indicated by the line BB' and leads the voltage E_2 by the angle α .

80 Since the torque developed by the spiral control spring is independent of the electrical energization conditions of the relay, the torque thus derived may be represented as a constant or

$$T_1 = K_1 = \text{torque due to spiral control spring.} \quad 90$$

The torque of the spiral control spring is considered to be in a contact-closing direction and is therefore made positive. From the above consideration of the torques developed by the elements A and B, the respective torque equations 105 may be written, and for the conditions represented by the vector diagram, the torque developed by element A is positive and the torque developed by element B is negative.

$$T_2 = K_2 E_1 E_3 \cos(\theta - \alpha) = \text{torque produced by the voltage and phasing coils of element A.} \quad 110$$

$$T_3 = -K_2 E_2 E_3 \cos(\phi - \alpha) = \text{torque produced by the voltage and phasing coils of element B.} \quad 115$$

The same proportionality constant, K_2 , has been used because it is assumed that the two elements have been balanced so that they produce equal torques under the same electrical conditions. The torque T_3 is indicated as negative because when the voltages E_2 and E_3 are nearly in phase, so that $\theta - \alpha$, and the cosine term is equal to plus one, the torque developed by element B is in contact-opening direction. 120

$$T_4 = K_3 E_1^2 = \text{torque from overvoltage adjuster of element A.}$$

$$T_5 = K_4 E_2^2 = \text{torque from overvoltage adjuster of element B.} \quad 130$$

The two torques T_4 and T_5 are obtained by assuming that the overvoltage adjusters of elements A and B are so positioned that a definite amount of torque is produced when only the respective voltage coils are energized, and the constants K_3 and K_4 are made different, assuming that the adjustments are different on the two elements. 135

The total torque developed by the synchro-verifier or relay is equal to the algebraic sum of 140 all of the respective torques, or

$$T_0 = T_1 + T_2 + T_3 + T_4 + T_5$$

To obtain the operating curve, the total torque, T_0 , must be equal to zero, or 145

$$K_1 + K_2 E_1 E_3 \cos(\theta - \alpha) - K_2 E_2 E_3 \cos(\phi - \alpha) + K_3 E_1^2 + K_4 E_2^2 = 0 \quad (1)$$

Since

$$\phi = \theta - \beta$$

150

and

$$\cos(\phi-\alpha) = \cos\phi \cos\alpha + \sin\phi \sin\alpha$$

$$\cos\phi = \cos(\theta-\beta) = \cos\theta \cos\beta + \sin\theta \sin\beta$$

$$\sin\phi = \sin(\theta-\beta) = \sin\theta \cos\beta - \cos\theta \sin\beta$$

then

$$\cos(\phi-\alpha) = \cos\alpha (\cos\theta \cos\beta + \sin\theta \sin\beta) + \sin\alpha (\sin\theta \cos\beta - \cos\theta \sin\beta) \quad (2)$$

From Fig. 5,

$$\cos\beta = \frac{E_1 + E_3 \cos\theta}{E_2}$$

15 and

$$\sin\beta = \frac{E_3 \sin\theta}{E_2}$$

Substituting the above values for $\cos\beta$ and $\sin\beta$ 20 in Eq. (2)

$$\cos(\phi-\alpha) = \cos\alpha \left[\cos\theta \left(\frac{E_1 + E_3 \cos\theta}{E_2} \right) + \left(\frac{\sin\theta E_3 \sin\theta}{E_2} \right) \right] + \sin\alpha \left[\sin\theta \left(\frac{E_1 + E_3 \cos\theta}{E_2} \right) \left(\frac{\cos\theta E_3 \sin\theta}{E_2} \right) \right] \quad (3)$$

$$25 = \cos\alpha \left[\left(\frac{E_1 \cos\theta + E_3 \cos^2\theta}{E_2} \right) + \left(\frac{E_3 \sin^2\theta}{E_2} \right) \right] +$$

$$\sin\alpha \left[\left(\frac{E_1 \sin\theta + E_3 \sin\theta \cos\theta}{E_2} \right) - \right]$$

$$30 \left(\frac{E_3 \sin\theta \cos\theta}{E_2} \right) - \frac{1}{E_2}$$

$$(E_1 \cos\theta \cos\alpha + E_3 \cos^2\theta \cos\alpha + E_3 \sin\theta \cos\alpha + E_1 \sin\theta \sin\alpha + E_3 \sin\theta \cos\theta \sin\alpha)$$

$$35 \cos(\phi-\alpha) = \frac{1}{E_2} [E_1 \cos(\theta-\alpha) + E_3 \cos\alpha] \quad (4)$$

Substituting the value of $\cos(\phi-\alpha)$ from Eq. 40 (4) in Eq. (1),

$$K_1 + K_2 E_1 E_2 \cos(\theta-\alpha) - K_3 E_2 E_3 \left[\frac{E_1 \cos(\theta-\alpha) + E_3 \cos\alpha}{E_2} \right] + K_4 E_1^2 + K_4 E_2^2 = 0$$

$$45 K_1 - K_2 E_3^2 \cos\alpha + K_3 E_1^2 + K_4 E_2^2 = 0$$

$$K_2 E_3^2 \cos\alpha = K_1 + K_3 E_1^2 + K_4 E_2^2 \quad (5)$$

It will be seen from Eq. (5) that Eq. (1) has been simplified by eliminating the ϕ term. In order to simplify Eq. (5) it is possible to eliminate the E_2 term by substituting the equivalent therefor in terms of E_1 , E_3 and $\cos\theta$. Since,

$$E_2^2 = (E_1 + E_3 \cos\theta)^2 + (E_3 \sin\theta)^2,$$

55 from Fig. 5,

$$E_2^2 = E_1^2 + E_3^2 + 2E_1 E_3 \cos\theta$$

Eq. (5) now becomes

$$60 K_2 E_3^2 \cos\alpha - K_4 (E_1^2 + E_3^2 + 2E_1 E_3 \cos\theta) = K_1 + K_3 E_1^2 E_3^2 (K_2 \cos\alpha - K_4) - 2K_4 E_1 E_3 \cos\theta = K_1 + E_1^2 (K_3 + K_4)$$

$$65 E_1^2 - E_1 \left(\frac{2K_4 E_1}{K_2 \cos\alpha - K_4} \right) \cos\theta = \frac{K_1 + E_1^2 (K_3 + K_4)}{K_2 \cos\alpha - K_4}$$

Let

$$M = \frac{K_1 + E_1^2 (K_3 + K_4)}{K_2 \cos\alpha - K_4}$$

70 and let

$$N = \frac{2K_4 E_1}{K_2 \cos\alpha - K_4}$$

$$E_3^2 - E_3 N \cos\theta = M$$

$$75 E_3^2 - E_3 N \cos\theta - M = 0 \quad (6)$$

$$E_3 = \frac{N \cos\theta \pm \sqrt{(N \cos\theta)^2 + 4M}}{2}$$

$$E_3 = \frac{N \cos\theta}{2} \pm \sqrt{\left(\frac{N \cos\theta}{2} \right)^2 + M} \quad (7) \quad 80$$

In Eq. (7), if $K_3 = K_4 = 0$

$$M = \frac{K_1}{K_2 \cos\alpha}$$

and $N = 0$

Therefore, when no torque is produced by either element when only the voltage coils are energized, the value of the difference or phasing voltage E_3 becomes,

$$E_3 = \pm \sqrt{\frac{K_1}{K_2 \cos\alpha}} \quad (8)$$

This equation shows that E_3 is a constant when K_3 and K_4 are zero, and therefore that the locus 95

of the torque-balance points is a circle with its 100 center at the terminus of vector E_1 , as in Fig. 4.

From the above mathematical derivation it may be seen that the terms M and N , in Eq. (7), are constant for any given set of adjustments for the synchro-verifier or relay, and for any 105 given value of E_1 . Thus, for a given value of E_1 and given relay adjustments, the operating curve of the relay may be determined from Eq. (7) in terms of E_3 and the angle θ .

As mentioned hereinbefore, the electrical 110 torques developed by elements A and B are usually opposed and it is only under certain phase-angle relations between the difference voltage and the potential coil voltages of the respective

115

elements, or when the phasing voltage is zero and the overvoltage adjusters are ineffective, 120 that the respective torques are not opposed.

Fig. 6 is illustrative of the general relation between the potential coil voltages of the elements A and B and the phasing voltage for different 125 adjustments of the spiral control spring and with the overvoltage adjusters of each element positioned for zero torque from the potential coils alone. The reference voltage is again assumed to be E_1 and the difference voltage E_3 is shown leading E_1 . The operating circles 101, 102, 103, 130 104 and 106 are obtained by changing the tension 104 and 106 on the spiral control spring, the torque delivered thereby being in a positive or contact-closing direction. In view of the characteristics of the 135 present invention, as evidenced by the above mathematical derivation, the effective value of the difference voltage E_3 is a function of the initial torque imparted to the spiral control spring. Obviously, the diameters of radii of all of the possible operating circles also vary in accordance with the initial tension of the spring; the smaller the operating circle the smaller the spring torque.

With the vector relation of the voltages E_1 and E_2 , as shown, the contacts of the relay will be 140 maintained in open position when the spiral control spring is adjusted for either of the operating circles 101 or 102, and the contacts would be held closed when the spiral control spring is adjusted 145 to provide operating circles 103, 104 or 106.

150

Referring to Fig. 6 again, and assuming the relay to be adjusted for operating circle 103 and the voltages E_1 and E_2 to be as shown, a definite amount of time is required for the relay contacts to be closed, depending upon the respective torques and the damping effect provided by the permanent magnet. Obviously, the amount of time required for the relay contacts to close, under energized conditions, may be varied by 10 adjusting the position of the damping magnet and by moving both of the upper pole structures of the two electro-magnet elements. Assuming any definite time required for the contacts to be closed after the phasing or difference voltage E_3 falls within the operating circle 103, it is obvious that this time determines the beat frequency which may exist between the voltages E_1 and E_2 , and still permit the closing of the relay contacts. In other words, assuming a beat frequency to 20 exist between the voltages E_1 and E_2 , the time required for the relay to close its contacts after the phasing or difference voltage falls within the operating circle 103 must be less than the time required for the voltage E_2 to move through the 25 operating circle 103 in order for the relay contacts to close. This will be explained in more detail later.

From the above, it may be seen that by changing the characteristics of the relay to effect the 30 closing of the contacts within any predetermined time, the permissible beat frequency between the two voltages may be varied at will. It is quite obvious that the contacts separation may be changed to effect different time intervals of operation of the relay, and the stationary contact is therefore made adjustable.

Assuming that E_2 is equal to E_1 , is in phase with E_1 , and is of the same frequency so that the two vectors shown for E_2 and E_1 coincide, under 40 this condition, the synchro-verifier will close its contacts after a predetermined time from the extreme open position, when operating circle 103 is being used. Assuming the required time to be five seconds, it is obvious that since no electrical 45 torque is produced, the closing torque developed by the spiral control spring is effective in closing the contacts at the greatest possible speed. Under the same electrical conditions, the contacts would close at a much slower rate if operating circle 101 50 was being used, due to the decrease in the amount of spring tension.

Assume the electrical conditions to be the same with the exception that the two voltages are of different frequencies, so that E_2 slowly moves 55 through the operating circle 103 at a uniform rate of speed, and that approximately five seconds are required for it to move from 15° lagging to 15° leading with respect to E_1 . Under this condition the contacts will not close if operating circle 103 is being used since zero resultant torque is produced when E_2 is 15° lagging and maximum resultant torque is produced when E_2 is in phase with E_1 . As assumed above, five seconds is required for the contacts to close when 65 the two voltages are in phase, so it obviously follows that a longer time is required for the contacts to close when the two voltages are of a different frequency. The time of five seconds required for E_2 to move through operating circle 70 103 at a uniform rate of speed corresponds to a beat frequency of approximately 1/60 cycle when the two systems are of normal 60 cycle frequency, so that a beat frequency of less than 1/60 cycle is required before the contacts will 75 close if operating circle 103 is being used. This

beat frequency is obtained by assuming the operating circle 103 to limit the effective rotation of E_2 from 15° lagging to 15° leading with respect to E_1 .

From the foregoing, it is clear that corresponding smaller beat frequencies are required for the contacts to close if operating circles with smaller diameters than 103 are being used. It is further apparent that for any given diameter of operating circle being used, the permissible beat frequency is changed when the magnitudes of the two voltages E_2 and E_1 are changed.

In Fig. 7 the relay characteristics are such that operating circle 107 is obtained by adjusting the initial tension of the spiral control spring and with a zero overvoltage adjustment on both electro-magnet elements. The synchro-verifier contacts will be closed, providing the voltage vector E_2 remains within operating circle 107 for a sufficient time, and it is clear that only a small phase-angle difference is permissible. Assuming the voltage E_1 to be reduced in magnitude as indicated by the vector E_1' , the operating circle remains the same since the diameter thereof is determined solely by the spring tension. With such reduced voltage condition, it is clear that a larger phase-angle difference may exist between the reduced voltage E_2' and the reference voltage E_1' . The operating circle 107' is of the same diameter as operating circle 107 and, irrespective of the voltage magnitudes, for any predetermined spring setting, the diameter of the relay operating circle remains constant.

In Figs. 6 and 7 the synchro-verifier is provided with a zero overvoltage adjustment and in this case the constants K_3 and K_4 are zero and Eq. (8) applies.

Referring to Fig. 8 the spiral control spring is adjusted to produce an initial negative torque and the relay contacts are maintained in open position when the two electro-magnet elements are deenergized. The overvoltage adjuster of each element is adjusted to produce a positive or contact closing torque and it may be noted that the center of the resulting operating circle 108 does not coincide with the end of the E_1 voltage vector, and further, that when the voltage E_1 is reduced to a value as indicated by the vector E_1' , the diameter of the operating circle is materially reduced, as shown by operating curve 109.

Assuming the overvoltage adjustment on element B is made zero so that the N term in Eq. (7) drops out, and that the overvoltage adjustment of element A is made positive, the mathematical expression indicates that the center of the operating circle should coincide with the end of the voltage vector E_1 , and that the diameter of the operating circle is determined as a function of the spring tension and the square of the potential coil voltage of element A. However, with relay characteristics corresponding to the Fig. 8 representation, both of the elements A and B are provided with an overvoltage adjustment and the diameter of operating circle 108 is determined by the spring tension and both of the potential coil voltages squared.

The operating curve 109 is obtained by leaving the relay adjustments the same as for curve 108 and decreasing the voltage to the value indicated by the voltage vector E_1' . This reduction of voltage effects a corresponding decrease in the positive torque produced by the overvoltage adjusters with the result that the diameter of the operat-

ing circle is materially reduced and the relay made more sensitive.

It is of interest to note that with the relay adjusted for the characteristics shown in Fig. 7, the sensitivity is decreased with decrease in voltage, while the relay is more sensitive for reduced voltage conditions when adjusted for the characteristics shown in Fig. 8.

Fig. 9 represents the relay characteristics when a negative spring tension is utilized and the balance is destroyed between the two electro-magnet elements by the adjustment of only the overvoltage adjuster of element A to effect a positive torque. As referred to hereinbefore, this adjustment of the relay should provide that the centers of the operating circles coincide with the end of the voltage vector E_1 . It will be observed, however, that according to Fig. 9, the centers of the operating circles do not coincide with the end of vector E_1 . The apparent contradiction is due to the action of the overvoltage adjuster in acting as a lag loop in the phasing coil magnetic circuit in addition to its expected function of acting as a lag loop for part of the potential coil flux.

The effect is relatively small for a small movement of the overvoltage adjuster but rapidly increases as the movement of the overvoltage adjuster increases. With the increased movement of the over-voltage adjuster, the impedance and power factor angle of the phasing coil circuit of element A is affected more, and the balance between elements A and B is disturbed and the formulas derived in the mathematical analysis will not apply. The operating curve 111 is shown with its center slightly removed from the end of vector E_1 , and the operating circle 112 is obtained by an increased movement of the overvoltage adjuster, with the result that the center thereof is substantially removed from the end of vector E_1 . The operating circles 113 and 114 correspond to the relay characteristics as adjusted for operating circles 111 and 112, respectively, when the voltage E_1 is reduced to the value shown by voltage vector E_1' .

The centers of the operating circles may be made to coincide with the end of voltage vector E_1 were the same kind of operating torque, as provided by the overvoltage adjuster, introduced by a means which would not affect the impedance of the phasing circuit. Obviously this means could be in the form of a third element which would produce a torque proportional to E_1^2 . This third element could be associated with one of the disc members and a fourth element, for introducing a torque proportional to E_2^2 , could also be provided and either be associated with one of the disc members, or the third and fourth members could cooperate with a third disc member to effect any desired torque proportional to E_1^2 , E_2^2 , or both.

In the above explanation of the relay characteristics, as shown in Fig. 9, the operating circles having their centers removed from the end of voltage vector E_1 were obtained by changing the impedance and power factor angle of the phasing coil magnetic circuit of element A. It follows, therefore, that any desired relay characteristics may be obtained by altering the impedance and power factor angle of either phasing coil magnetic circuit, or both.

Referring to Fig. 10, the various operating curves 116, 117, 118, 119, 121 and 122 may be obtained by shunting the phasing coils with resistances, impedances or capacitances. For example, curve 116 results when the phasing coil of

element B is shunted by a relatively large resistance. The radii of all of the respective operating curves shown in Fig. 10 indicate the position of the centers of the operating curves relative to the end of voltage vector E_1 . Curve 117 may be obtained by shunting the phasing coil of element B with a smaller resistance and operating curve 118 may be obtained by shunting the phasing coil of element B with an equivalent impedance. Operating curve 119 may be obtained by shunting the phasing coil of element A with an equivalent impedance and curves 121 and 122 may be obtained by shunting the phasing coils of elements A and B, respectively, by a small capacitance. The various operating curves illustrated in this figure have been indicated in a purely arbitrary manner and it is to be understood that by altering the type and magnitude of the shunting means, the position of the respective centers and the length of the radii may be modified at will.

In this respect an operating circle, similar to operating curve 123 in Fig. 11, may be obtained with the result that the relay contacts will not be permitted to close until the voltage vector E_2 falls within this curve and remains there for a predetermined time. Such relay characteristic is particularly advantageous in the application of the relay to network distribution systems, wherein it is desirable to permit the closing of a network switch or circuit interrupter only when the current which flows after the switch is closed, is in a direction to insure power flow from a feeder circuit to a network load.

Assuming the potential coil of element A energized in accordance with the network voltage, the potential coil of element B energized in accordance with the feeder voltage and the respective phasing coils energized in accordance with the difference or phasing voltage across the break contacts of the network switch, the relay or synchro-verifier may be adjusted for the characteristic operating curve 123 as shown in Fig. 11. In this figure E_1 represents the network voltage and E_2 represents any possible feeder voltage with the resulting phasing or difference voltage E_3 . The operating curve 123 is confined to substantially the leading quadrant, considering the voltage vector E_1 as the reference voltage, and it is necessary for the feeder voltage E_2 to terminate within this circle and remain there for the necessary predetermined time for the relay contacts to be actuated to closed position.

By confining the range within which the phasing voltage may fall to substantially the leading quadrant with respect to the network voltage E_1 , the relay effects the closing of the network switch, and the current which flows as a result of this phasing voltage will not lag sufficiently to cause power to flow from the network to the feeder. In other words, since a usual directional relay is provided for effecting the automatic opening of the network switch, such relay would not be effectively energized to immediately open the network switch when the switch is closed and the phasing voltage leads the network voltage.

Assuming any phasing voltage to exist across the break contacts of the network switch, theoretically the resulting current flow would lag this voltage by an angle of 90° when the network load is purely inductive. In practice, however, this angle of lag usually falls within a range of between 20° and 70° and so it is inadvisable to permit the effective phasing voltage to lag the network voltage by an angle greater than 20° . Since the closing range should be limited as above stated, the

relay of the present invention, provided with characteristics similar to the Fig. 11 adjustment, may be used very advantageously in network systems for effecting the proper closing of a network switch.

The application of the present invention to network systems offers a further advantage in that the feeder and network voltages must be substantially of the same frequency. This condition is not fulfilled in the majority of the present network installations, and depending upon the characteristics of any particular distribution system, this feature is quite advantageous.

In the foregoing explanation relating to the vector diagrams comprising Figs. 6 to 11, inclusive, only a general relation between two system voltages is considered and the relay characteristics vectorially represented in Figs. 6 and 7 were determined with a zero adjustment of the over-voltage adjusters while the remaining figures are illustrative of different possible adjustments of the overvoltage adjusters, or the equivalent thereof.

Fig. 12 is a schematic wiring diagram of a usual application of the present invention for verifying the condition of synchronism between two energized systems. One system 126 is represented as a long transmission system or section of a loop or ring system and is adapted to be energized from a bus or feeder circuit 127 through circuit breaker 128. The system 126 and bus 127 are shown as three-phase circuits, only for purpose of explanation, and it is obvious that any alternating-current circuits may be understood as being proper for the application of the present synchronizing arrangement.

A second system 129 is also represented as any proper alternating-current circuit and is adapted to be energized from any suitable source, as bus 131, through circuit breaker 132.

Assuming that the two circuits 126 and 127 are adjacent sections of a loop system and that a connecting circuit breaker 133 has been actuated to its open position, as shown in the drawings, this breaker should not be closed unless the characteristics of the two circuit voltages are related within a predetermined range of electrical conditions.

For this purpose the synchro-verifier is provided and is indicated schematically as comprising the two electro-magnet elements A and B, the respective disc elements 13, spindle 26, gears 47 and 53, spiral control spring 67, moving contact 54 and stationary contact means 68. The phasing and voltage windings of the elements A and B are indicated by 11 and 12, respectively, and the upper pole laminations 8 of both elements A and B are properly positioned with respect to the lower pole laminations 9, so that equal and opposite torques are produced when the two elements are energized under the same electrical conditions. In this application of the present invention, the overvoltage adjusters (not shown) are adjusted for zero torque condition and the relay operates in accordance with the characteristics shown in Figs. 6 and 7. The diameter of the desired operating curve is determined solely by the initial positive tension imparted to the spiral control spring 67 and, therefore, under deenergized conditions the relay contacts 68 are bridged by the moving contact 54.

A voltage transformer 134 is electrically connected across one phase of the circuit 126 and a second voltage transformer 136 is electrically connected across the corresponding phase of the circuit 129. One terminal of the secondary

winding of transformer 134 is connected to the secondary terminal of corresponding polarity of transformer 136 by means of conductor 137, and is grounded at 138. The other secondary terminal of transformer 134 is connected to one terminal connection of the voltage winding 12 of element A by conductor 139 through contacts 141 and pallet switch 142 associated with the breaker 133. The other terminal connection of the voltage winding 12 is connected to the conductor 137 to thereby effect the energization of the winding 12 in accordance with the secondary voltage of transformer 134.

The remaining secondary terminal connection of transformer 136 is connected to one terminal connection of the voltage winding 12 of element B through contacts 143 and pallet switch 144 of the breaker 133, and conductor 146. The remaining terminal of the voltage winding 12 is connected to the conductor 137, thereby completing the energization thereof in accordance with the voltage of circuit 129 when the circuit breaker 133 is in open position.

The phasing winding 11 of element A has one terminal connected to the conductor 139 while the other terminal is connected to conductor 146 through a resistor 147. The phasing winding 11 is, therefore, energized in accordance with the difference or phasing voltage between the systems 126 and 129. The resistor 147 is provided for the protection of the winding 11 in the event of the two system voltages being 180° out of phase, in which case the difference voltage may be twice normal.

The phasing winding 11 of element B is connected to the conductors 139 and 146, in parallel with the phasing winding 11 of element A, and a resistor 148 is provided in series with winding 11 for the protection thereof under the above mentioned out-of-phase condition.

One of the relay contacts 68 is connected to conductor 139 and the other contact 68 is connected to the energizing winding 149, of an induction type relay 151, through resistor 152, and the circuit is completed from the winding 149 to the conductor 137. The winding 149 is energized in accordance with the voltage across the secondary winding of transformer 134 and the resistor 152 is provided for protecting the contacts of the synchro-verifier.

The voltage relay 151 is shown schematically as comprising a C-magnet 153 having a shading coil 154 and a disc armature 156 adapted to be rotated in accordance with the energization of winding 149, a spindle 157 adapted to be rotated by the disc 156, a contact 158 carried by said spindle and stationary contacts 159 adapted to be closed by contact 158. The rotation of the armature 156 is damped by a permanent magnet 161, and with the winding 149 deenergized, a spiral spring 162 serves to maintain the contact 158 out of engagement with the stationary contacts 159.

One of the contacts 159 is connected to one line of any suitable direct current source or bus 163 and the other contact 159 is connected to the other line of the bus 163 through the closing coil 164 of the circuit breaker 133. Contacts 166 are associated with the breaker 133 and are adapted to be bridged by pallet switch 142 to complete a holding circuit for the closing coil 164 from the source 163, upon the actuation of the circuit breaker 133 to its closed position. Means for deenergizing the winding 164 is indicated generically as a normally closed push button 167.

- Assuming only the circuit 126 to be energized and, therefore, the circuit breaker 133 to be in open position, the voltage coil 12 of element A is energized by the full secondary voltage of potential transformer 134 and the phasing coils 11 of elements A and B are energized in parallel, the parallel phasing coils being connected in series with a parallel circuit comprised of the voltage coil 12 of element B and the secondary winding 10 of the potential transformer 136. Consequently, a strong torque is produced in the contact opening direction. Similarly, if only the circuit 129 is energized, the coils 11 and 12 will be energized in like manner, except that voltage coil 12 of element B will have full voltage impressed across it, and a negative or contact-opening torque will be produced. If both circuits 126 and 129 are de-energized, the contacts 68 would be bridged by the arm 54 due to the action of the spring 67.
- 20 If the contacts 68 were connected directly to the breaker closing coil 164, the circuit breaker 133 would be closed as soon as either circuit 126 or circuit 129 were energized. Although a contact-opening torque would be produced upon the energization of either circuits 126 or 129, the contacts 68, being initially closed by the arm 54, would not be opened quickly enough to prevent closure of circuit breaker 133.

To show the undesirability of such operation, assume both circuits 126 and 129 to be deenergized, and a fault, such as a short-circuit between conductors, to exist on circuit 129. Then when circuit 126 is energized, the circuit breaker 133 will close in upon the fault. It will be opened by automatic means, not shown, for interrupting the holding circuit to the coil 164, and this will cause the breaker to rupture a current of high magnitude. This is an unnecessary operation and tends to injure the breaker. When the relay 151 is used, the contacts 68 will be opened before the contacts 159 are closed. Thus the coil 149 of the relay 151 will be deenergized and the contact arm 158 will reset.

The connections of Figure 12 therefore should not be used except where provision is made for energizing the two separated circuits, such as circuits 126 and 129 at their opposite ends. When the circuits are thus energized, the synchro-verifier connected as in Figure 12, will operate to connect the two circuits, as through breaker 133, if the two voltages have the correct relations. The synchro-verifier can be used, in conjunction with other relay means, for connecting the distant ends of circuits 126 and 129 to sources of energy, and such an application will be described later. The requirements of such an application include the closure of the circuit breaker between the source and circuit when one or both are deenergized, and it has been shown that the connections of Figure 12 are not suitable for this.

In accordance with the above-mentioned application of the present invention and assuming both circuits 126 and 129 to be energized, the circuit breaker 133 is actuated to its closed position upon the bridging of contacts 159 by the contact arm 158 of relay 151. If the voltages, frequencies and phase displacement of the circuits 126 and 129 are such that the adjustments of the synchro-verifiers permit the contacts 68 to be closed, the winding 149 of relay 151 will be energized in accordance with the secondary voltage of transformer 134 and the contacts 159 are bridged only after a predetermined time depending upon the amount of damping provided by the magnet 161, the restraining action of the spring 162 and

the amount of separation between the contact 158 and contacts 159. The bridging of contacts 159 completes the energizing circuit for the closing winding 164 from the direct current source 163 and the circuit breaker 133 is actuated to its closed position, the winding 164 being continuously energized by means of the holding circuit through contacts 166 and pallet switch 142. The section 129 is, therefore, connected to the section 126 and the circuit breaker 133 remains closed until some circuit breaker opening means, as push button 167 in the holding circuit for winding 164 is actuated upon the occurrence of any predetermined electrical conditions or at the will of the station operator.

Next assuming the circuit breaker 133 to be at the other end of the section 129, and the section 126 to be adjacent thereto, the breaker 133 will not be closed until the voltages of sections 126 and 129 bear the proper relation required by the particular characteristics for which the synchro-verifier is adjusted. Assuming the two circuit voltages to be improper for the closing of breaker 133, the voltage relay 151 acts to introduce a time delay in the energization of the closing coil 164 and this time delay, in the bridging of contacts 159, permits the synchro-verifier to effect the rotation of the contact arm 54 out of engagement with contacts 68 and thereby effect the deenergization of the circuit for winding 149 of relay 151.

As pointed out hereinbefore a definite amount of time is required in effecting the closing of the synchro-verifier contacts for any given relation between the two circuit voltages, and since the permissible beat frequency is regulated by this time lag, the provision of the voltage relay 151 results in an appreciable lowering of the permissible beat frequency and the synchronizing arrangement is thus made more sensitive.

The provision of the voltage relay 151 is recommended whenever the synchro-verifier is adjusted for the characteristics shown in Figs. 6 and 7. This application of the additional relay 151 is quite obvious since the synchro-verifier contacts are normally closed and improper closing of the associated circuit breaker is therefore made possible.

In some synchronizing applications, it may be desirable to increase the sensitivity of the synchro-verifier when the magnitudes of the two system voltages are decreased or the provision of the additional relay 151 may be objectionable from the customer's standpoint. In this case, the synchro-verifier may be adjusted for the characteristics shown in Fig. 8.

Assuming the synchro-verifier to be adjusted for characteristics as shown in Fig. 8 and the contacts 68 to directly control the energizing circuit of the winding 164, the relay 151 may be eliminated from the synchronizing arrangement. With the synchro-verifier so adjusted, the contact 54 is normally held out of engagement with contact 68 by a negative or contact opening torque produced by the spiral control spring 67, and the overvoltage adjusters of elements A and B are adjusted for the desired operating curve. Obviously this simple arrangement may be used effectively in many synchronizing applications and only in cases where a longer time delay or smaller beat frequency is required, will it be necessary to include the relay 151 in the synchronizing circuit.

It is further clearly apparent that some relay applications warrant and require the adjustment of the synchro-verifier for characteristics similar

to those shown in Figs. 9, 10 and 11. In this respect, one application will be considered when the synchro-verifier is adjusted for the characteristics shown in Fig. 11.

6 Referring to Fig. 12 again, assume the three-phase circuit 129 to be energized from the secondary of a distribution transformer (not shown) and the feeder 131 to be energized from a central station and supplying power through circuit breaker 133 to the primary of the said transformer. Next consider the three-phase circuit 126 to be connected to a network load (not shown) and regard the bus or feeder 127 as an additional feeder supplying power to the network load from a different source. The circuit breaker 133 now constitutes a so-called network switch and proper relay apparatus must be associated therewith for effecting the automatic actuation thereof under predetermined electrical conditions.

10 Assuming the network load to be energized by means of the feeder circuit 127 and that it is desired to connect the additional feeder 131 thereto, the circuit breaker 132 is actuated to its closed position by the central station operator, in any 15 suitable manner. Both the feeder circuit 129 and the network load circuit 126 are now energized and the synchro-verifier is, therefore, energized in accordance with the voltages of the two circuits. In this application it is to be remembered 20 that the contact arm 54 is normally held out of engagement with contacts 68 by reason of the negative torque produced by the spiral control spring 67 and further, that the contacts 68 are connected directly in the energizing circuit for 25 the circuit breaker closing winding 164.

As required by the relay characteristics shown in Fig. 11, the feeder voltage which is obtained by means of voltage transformer 136, must be greater, than the network voltage obtained by 40 means of voltage transformer 134. It is further required that the difference or phasing voltage energizing the phasing windings 11 of both elements fall approximately within the leading quadrant with respect to the network voltage.

45 Theoretically this requirement should be met, considering the network load to be highly reactive, but in practice it has been found that the current which flows through the network switch after it closes, lags the voltage across the break contacts of the network switch by an angle of from 20° to 70°. It follows, therefore, that the closing range or operating curve may fall in the lagging quadrant with respect to the network voltage, providing the maximum permissible lag 50 of the phasing voltage does not exceed 20°, and the current which flows as a result of such phasing voltage will never lag the network voltage by an angle greater than 90°. In this manner, assuming a directional relay to be provided for effecting the opening of the network switch upon the occurrence of power flow from the network to the feeder, the network switch is not permitted to be closed unless the resulting current flow is from the feeder to the network load, thus insuring proper power flow to the network load and preventing the repeated opening and closing or "pumping" of the network switch.

55 The synchro-verifier is, therefore, energized in accordance with the feeder and network voltages and, in accordance with the characteristics imparted to the relay, the contacts 68 are only bridged by the contact 54 and the circuit breaker closing coil 164 energized when the current which flows through the network switch 133 after it is closed is in a direction to maintain it closed. Ob-

viously, any directional relay for effecting the opening of the network switch 133 upon the occurrence of a flow of power from the network 126 to the feeder 129, may be associated with a switch such as push button 167 for de-energizing the holding circuit of winding 164.

60 A more general application of the present invention is shown in Fig. 13 of the drawings and includes a relay arrangement associated with the synchro-verifier for insuring the closure of a circuit breaker associated with two systems under any predetermined energized or deenergized system conditions.

65 Referring to the drawings, a bus 171 is adapted to be energized from any suitable power source (not shown) through feeder 172 and circuit breaker 173. An incoming line or load section 174 is adapted to be energized from any suitable source (not shown) through feeder 176 and circuit breaker 177. The purpose of the present invention is to effect the automatic closing of a circuit breaker 178 associated with the circuits 171 and 174.

70 The synchro-verifier is shown schematically as comprising elements A and B, the respective phasing and voltage windings being indicated by 11 and 12, respectively. Disc elements 13 cooperate with elements A and B to effect the rotation of spindle 26, and moving contact 54 is associated therewith through gears 47 and 52 and 75 is adapted to bridge stationary contacts 68. The spiral control spring 67 is also shown and is adjusted for an initial positive or contact closing torque.

75 One secondary terminal of transformer 181 is connected to the secondary terminal of opposed polarity of transformer 182 by conductor 183, and the conductor 183 is grounded at 184. The other secondary terminal of transformer 181 is connected to one terminal of the voltage winding 12 of element A by means of conductor 186 through contacts 187 and pallet switch 188 of the breaker 178. The energizing circuit for this winding 12 is completed by connecting its other terminal to conductor 183, thereby resulting in the energization of winding 12 of element A in accordance with the secondary voltage of transformer 181 when the circuit breaker 178 is in open position.

80 The remaining secondary terminal of transformer 182 is connected to one terminal of winding 12 of element B by conductor 189 through contacts 191 and pallet switch 192 associated with the breaker 178. The remaining terminal of the winding 12 is connected to conductor 183 to thereby effect the energization thereof in accordance with the secondary voltage of transformer 182 when breaker 178 is in open position.

85 One terminal of each phasing winding 11 of elements A and B is connected to conductor 186 and the remaining terminals are connected to conductor 189 through resistance elements 193 and 194, respectively. The phasing windings 11 are thus connected in parallel and energized in accordance with the difference voltage between the two systems 171 and 174. The resistance elements 193 and 194 are provided for protecting the phasing windings 11 when the two system voltages are substantially out of phase.

90 One of the stationary contacts 68 is connected to conductor 186 and the other contact 68 is connected to one terminal of the energizing winding 196 of an induction disc type voltage relay 197, the remaining terminal of winding 196 being connected to conductor 183 through a resistance 198. The relay 197 is shown schematically as com-

- prising a C-magnet 199 and a short-circuited turn 201, disc element 202, spindle 203, restraining spring 204, moving contact 205, stationary contacts 206 and damping magnet 207. It may be noted that the energizing winding 196 is energized in accordance with the secondary voltage of transformer 181 when the synchro-verifier contacts 68 are bridged by contact 54 and the resistance 198 is employed for the protection of the synchro-verifier contacts.
- A second voltage relay 208, substantially similar to relay 197, has one terminal of its energizing winding 209 connected in series with resistance 211 and thence to conductor 183 and the other terminal connected to conductor 186. The schematic representation of relay 208 comprises a C-magnet 212, short-circuited turn 213, disc element 214, spindle 216, restraining spring 217, moving contact 218, stationary contacts 219 and 221, and damping magnet 222.
- The energizing winding 209 of relay 208 is also energized in accordance with the secondary voltage of transformer 181. The contacts 219 are bridged by moving contact 218 under de-energized conditions of the relay 208 and the stationary contacts 221 are only bridged by contact 218 when the relay 208 is energized.
- A third voltage relay 223, substantially similar to relays 197 and 208, is represented schematically as comprising a C-magnet 224, main energizing winding 226, auxiliary winding 227, disc element 228, spindle 229, restraining spring 231, moving contact 232, stationary contacts 233 and 234, and damping magnet 236. One terminal of the energizing winding 226 is connected to conductor 189 through resistance 237 and the other terminal is connected to conductor 183. Thus, under de-energized conditions of the relay, the contacts 233 are bridged by moving contact 232. Under energized conditions of the relay, or when the winding 226 is energized in accordance with the secondary voltage of transformer 182, the stationary contacts 234 are bridged by moving contact 232.
- A relay 238, represented as being of the drum type, is adapted to be energized from a separate alternating current source or from the voltage source of feeder 172. A motor element 239 is adapted to drive a drum 241 having a contact member 242 thereon adapted for the bridging of stationary contacts 243. In the relay arrangement shown in this drawing, the voltage source for relay 238 will be assumed to be the power source for feeder 172.
- The operation of the arrangement shown in Fig. 13 for the different energized conditions of systems 171 and 174, is as follows:
- Assuming the circuit breakers 173 and 177 to be in open position, thereby disconnecting the feeders 172 and 176 from the bus 171 and section 174, respectively, it may be desired to close the circuit breaker 178 and connect the two circuits 171 and 174 before either circuit is energized. This closure of circuit breaker 178 is effected by energizing the relay 238 and bridging the stationary contacts 243 by the contact member 242. A circuit is thereby completed from the bus of a direct current source 244 through the normally bridged contacts 233 of relay 223, contacts 243 and contact member 242 of relay 238, energizing winding 246 of a voltage relay 247, resistance 248 and thence to the positive bus of the direct current source 244.
- The energization of the winding 246 of relay 247 effects the actuation of said relay to close contacts 249 by means of pallet switch 251 and thereby complete an energizing circuit for the closing coil 252 of circuit breaker 178. This energizing circuit may be traced from the positive bus of source 244, through the closing winding 252, contacts 249 and pallet switch 251 of relay 247, and thence to the negative bus of source 244.
- The actuation of the relay 247 also effects the bridging of contacts 253 by pallet switch 254 to complete a holding circuit for the energizing winding 246. This holding circuit may be traced from the positive bus of source 244, through the resistance 248 and winding 246, contacts 253 and pallet switch 254 of relay 246, and thence to the negative bus of source 244.
- From the foregoing explanation, it is clear that the circuit breaker 178 may be actuated to its closed position, even though circuits 171 and 174 are de-energized.
- Next assume that circuit 171 is energized from feeder 172 through circuit breaker 173. Transformer 181 is now energized and the voltage winding 12 of element A is energized in accordance with the transformer secondary voltage. The phasing coils 11 of elements A and B are energized in parallel and the two paralleled phasing coils are connected in series with a second parallel circuit comprised of the secondary of the potential transformer 182, the voltage winding 105 12 of element B and the winding 226 of relay 223. Since the impedance of the phasing windings 11 is relatively high, the winding 226 will not be sufficiently energized to actuate the relay 223, and the moving contact 232 will remain closed 110 against the stationary contact 233. The synchro-verifier will have a negative or contact-opening torque, so that the contact 54 will move away from the stationary contacts 68.
- The energizing winding 209 of relay 208 is also 115 energized in accordance with the secondary voltage of transformer 181 and the moving contact 218 is actuated to bridge contacts 221. Since the circuit 174 and the transformer 182 are de-energized, the relay 223 is de-energized and the contacts 233 are normally bridged by the moving contact 232 as a result of the torque exerted by the restraining spring 231.
- From an examination of the electrical connections between the contacts of relays 197 and 125 208, it will be seen that no electrical circuit is completed inasmuch as one of the contacts 206 of relay 197 is connected to one of the open contacts 219 of relay 208 and also to one of the open contacts 234 of the de-energized relay 223, the 130 other contact 206 of relay 197 is connected to one of the closed contacts 221 of relay 208, the other contact 221 being connected to the positive bus of source 244 through the energizing winding 246 of relay 247, and resistance 248. However, 135 this circuit is not completed to the negative bus of source 244 since the contacts 219 and 234 of relays 208 and 223, respectively, are not closed.
- From the above, it becomes clear that in order to close the circuit breaker 178 when the bus or 140 circuit 171 is energized and the circuit 174 is de-energized, the relay 238 must be energized, as explained hereinbefore, with reference to the closing of circuit breaker 178 when both of the circuits 171 and 174 are de-energized, with the result that the closing coil 252 of circuit breaker 178 is energized, the circuit being completed through the normally closed contacts 233 of relay 223.
- Now assume the feeder circuit breaker 173 to 150

be open and the bus or circuit 171 de-energized, and the feeder 176 to be supplying power to the circuit 174 through circuit breaker 177. Under these conditions the synchro-verifier is energized as in the previous case except that the voltage coil 12 of element B is now energized by the full secondary voltage of the transformer 182 and the voltage coil 12 of element A is energized at a much lower voltage since it is connected in series with the phasing windings 11. The windings 196 and 209 of the respective relays 197 and 208 are also substantially de-energized, the contacts 206 of relay 197 being open and the contacts 219 of relay 208 being bridged by contact 218.

15 However, the transformer 182 is now energized and the winding 226 of relay 223 is energized in accordance with the secondary voltage of transformer 182, with the result that the moving contact 232 is actuated to bridge contacts 234. An energizing circuit for the winding 246 of relay 247 is thus completed from the negative bus of source 244, contacts 234 and 232 of the relay 223, contacts 219 and 218 of the relay 208, through winding 246 of relay 247, resistance 248, push button switch 256 and thence to the positive bus of source 244.

The energizing circuit for the closing winding 252 of the circuit breaker 178 is effected by the actuation of the relay 247, as explained hereinbefore, and the circuit breaker is actuated to its closed position to connect the circuits 171 and 174. The winding 252 is continuously energized by virtue of the holding circuit for relay 247, the nature of which has been previously explained.

35 Now consider the bus or circuit 171 to be energized from the feeder 172 through circuit breaker 173, and the load section or circuit 174 to be energized from the feeder 176 through circuit breaker 177. The feeder circuits 172 and 176 are presumed to be energized from different sources with the possible result that the voltages of circuits 171 and 174 are dissimilar and the two circuits are not in synchronism.

40

Under such energized conditions, and considering the circuit breaker 178 to be in open position, the synchro-verifier is effectively energized to maintain the contacts 68 closed or to open contacts 68 by rotating the moving contact 54.

50 The voltage windings 12 of elements A and B are now energized in accordance with the secondary voltages of energized transformers 181 and 182, respectively, and the phasing windings of both elements are energized in accordance with the difference voltage existing between the two 55 secondaries of transformers 181 and the 182.

The winding 209 of relay 208 is energized in accordance with the secondary voltage of transformer 181 and the contacts 221 are bridged by contact 218. The winding 226 of relay 223 is energized in accordance with the secondary voltage of transformer 182 and the moving contact 232 is actuated to bridge contacts 234.

The energizing circuit for the winding 196 of relay 197 is only completed when the contacts 68 of the synchro-verifier are bridged by the moving contact 54. When the energizing circuit is completed, the winding 196 is energized in accordance with the secondary voltage of transformer 181 and the contacts 206 are bridged by contact 205.

Assuming the voltages of the two circuits 171 and 174 to be improperly related for the closing of the circuit breaker 178 with the synchro-verifier adjusted for any particular desired characteristics, the total resultant torque of the synchro-

verifier will be negative or in a contact opening direction. The contact 54 will, therefore, be rotated out of engagement with contacts 68 and the relay 197 will be deenergized. The relay 197 is so designed and adjusted as to introduce a predetermined time delay in the operation thereof and thereby permit the moving contact 54 of the synchro-verifier to be rotated out of engagement with the contacts 68 under improper circuit voltage conditions. Obviously when such condition exists and the contacts 68 are opened, the energizing circuit for the winding 196 of relay 197 is broken and the contacts 206 are not closed.

It is apparent from the arrangement of circuit connections between the various relay contacts that with contacts 206 of relay 197 open, contacts 221 of relay 208 bridged by contact 218, and contacts 234 of relay 223 bridged by contact 232, the energizing circuit for winding 246 of relay 247 is incomplete and the closing winding 252 of circuit breaker 178 is not energized to effect the closing of the breaker. This contact circuit is arranged by placing the contacts 206 of relay 197 in series with one of the contacts 221 of relay 208 and thence to one of the contacts 234 of relay 223. 100

It is obvious, therefore, that when the circuits 171 and 174 are energized, the synchro-verifier contacts 68 must be bridged by the contact 54 before the circuit breaker 178 is permitted to close, and, further, the synchro-verifier contacts must remain closed for a predetermined time, depending upon both the particular characteristics thereof and the time delay obtained by means of the relay 197, before the energizing circuit will be completed for the winding 246 of relay 247. 110

When the voltage of circuit 171 is properly related to the voltage of circuit 174 in magnitude, phase position, and frequency, as required by the particular characteristics for which the synchro-verifier is adjusted, the synchro-verifier contacts 68 will be bridged by contact 54 with the result that the winding 196 of relay 197 is energized and the relay contacts 206 bridged by contact 205 after a predetermined time. 110 115

The contacts 221 of relay 208 are bridged by contact 218 and the contacts 234 of relay 223 are bridged by contact 232, the control energizing circuit being completed only by the closing of contacts 206 of relay 197.

The above-mentioned control circuit may be traced from the negative bus of source 244, through contacts 234 and contact 232 of relay 223, contacts 206 and contact 205 of relay 197, contacts 221 and contact 218 of relay 208, through energizing winding 246 of relay 247, resistance 248, push button switch 256 and thence to the positive bus of source 244. The relay 247 is therefore actuated to close contacts 249 by means of pallet switch 251 with the result that the energizing circuit for the closing coil 252 of the circuit breaker 178, is completed from the negative bus of source 244, through contacts 249 and pallet switch 251 of relay 247, through winding 252, and thence to the positive bus of the source 244. Upon the energization of the winding 252, the circuit breaker 178 is actuated to its closed position to connect the circuits 171 and 174. The holding circuit for relay 247 has been explained hereinbefore and is completed by the closing of contacts 253 by means of pallet switch 254. A push button arrangement 256 is indicated generically in the holding circuit of relay 247 and may be actuated when desired, to effect the opening of circuit breaker 178.

From the foregoing description of the opera- 150

tion of the arrangement of Fig. 13, it may be concluded that the synchronizing arrangement of the present invention may be combined with suitable relays to effect the connection of two electrical circuits or systems when neither of the circuits are energized; when either one of the circuits is energized and the other circuit de-energized; and when both circuits are energized and the magnitude, phase position and frequency 10 of the two circuit voltages bear a predetermined relation.

Obviously, in the Fig. 13 arrangement, the synchro-verifier could be adjusted for the characteristics shown in Fig. 8 and the necessity for 15 the voltage relay 197 would not arise. With such an adjustment of the synchro-verifier, the contacts 68 would normally be open because of the initial negative torque of the spiral control spring 67 effecting the rotation of contacts 54 out of 20 engagement with the contacts 68. In this case, the contacts 68 would replace the contacts 206 of relay 197 in the control circuit hereinbefore described.

In the synchronizing arrangements shown in 25 Figs. 12 and 13, it is obvious that the circuit breaker, for connecting two systems, may be actuated to its closed position and latched by any suitable mechanical arrangement thereby obviating the necessity of maintaining the closing coil 30 energized. It is further apparent that any circuit breaker opening means may be employed, such as a directional relay in the application of the present invention to alternating-current network systems of distribution.

One modification of the present invention has 35 been described in detail and the more general applications thereof have been considered in order to better permit the proper application thereof. This invention is not to be limited to the exact 40 novel features disclosed because it is obvious that in view of the complete mathematical analysis included in the present specification, one skilled in the art may effect many modifications of the present invention and propose applications 45 thereof which may be considered as being properly within the spirit and scope of the present invention.

It is desired, therefore, that no limitations be imposed upon the present invention other than 50 required by the prior art and as indicated in the appended claims.

I claim as my invention:

1. In combination with two alternating-current 55 circuits and a switch for connecting said circuits, control means for said switch including a pair of electromagnetic elements arranged to produce opposing forces, means for energizing each of said elements in accordance with line voltage conditions derived from said circuits and difference voltage conditions determined by voltages across the break contacts of said switch, and means 60 responsive to the difference of forces exerted by said elements for closing said switch under predetermined electrical conditions of said circuits.

2. In combination with two alternating-current 65 circuits and a switch for connecting the circuits, control means for said switch including relay means and means for energizing said relay means in accordance with the circuit voltages and the 70 difference voltage across the break contacts of said switch, said relay means being adapted to produce a torque in accordance with one of the circuit voltages and the difference voltage and an opposed torque in accordance with the other 75 circuit voltage and the difference voltage.

3. In combination with two alternating-current 80 circuits and a switch for connecting the circuits, control means for said switch including relay means, means for effectively energizing said relay means in accordance with the voltages incident to said circuits only when said circuits are energized for effecting the closing of said switch under predetermined electrical conditions, and means operatively associated with said first 85 means and said switch for effecting the closing of said switch when only one of said circuits is energized.

4. In combination with two alternating-current 90 circuits and a switch for connecting the circuits, control means for said switch including a plural element relay means connected and arranged to be energized in accordance with the voltages incident to said circuits for effecting the closing of said switch only during predetermined phase and 95 frequency relations between the two circuit voltages and means electrically associated with said control means and said switch for effecting the closing of said switch when only one of said circuits is energized.

5. In combination with two alternating-current 100 circuits and a switch for connecting the circuits, control means for said switch including means connected and arranged to be effectively energized in accordance with the voltages incident to said circuits only when said circuits are energized 105 for effecting the closing of said switch under predetermined electrical conditions, means operatively associated with said first means and said switch for effecting the closing of said switch when only one of said circuits is energized and 110 means associated with said switch and said control means for effecting the closing of said switch when both of said circuits are de-energized.

6. In apparatus responsive to the condition of 115 synchronism of a pair of alternating-current circuits, a pair of watt-responsive elements and a movable member responsive to the algebraic sum 120 of forces produced by said elements, each of said elements having means including a pair of windings for producing a force proportional to the vector product of currents in said windings, means for energizing a winding of one of said elements in accordance with a voltage condition of one of said circuits, means for energizing a winding of the other of said elements in accordance 125 with the corresponding voltage condition of the other of said circuits, and means for energizing the remaining winding of each of said elements in accordance with the vector difference of 130 said voltage conditions, the relative directions of said windings being such that the forces produced by said elements normally oppose.

7. In apparatus responsive to the condition of 135 synchronism of a pair of alternating-current circuits, a pair of induction disc elements and a movable member responsive to the algebraic sum 140 of the torques of said elements, each of said elements having a pair of windings relatively positioned to produce a torque proportional to the vector product of currents in said windings, means for energizing a winding of one of said elements in accordance with a voltage condition of one of said circuits, means for energizing a winding of the other of said elements in accordance 145 with the corresponding voltage condition of the other of said circuits, and means for energizing the remaining winding of each of said elements in accordance with the vector difference of 150 said voltage conditions, the relative directions of

- said windings being such that the torques of said elements normally oppose.
8. In apparatus for automatically synchronizing a pair of alternating-current circuits, a switch for connecting said circuits, a pair of induction disc elements and a movable member responsive to the algebraic sum of the torques of said elements, each of said elements having a pair of windings relatively positioned to produce a torque proportional to the vector product of currents in said windings, means for energizing a winding of one of said elements in accordance with a voltage condition of one of said circuits, means for energizing a winding of the other of said elements in accordance with a corresponding voltage condition of the other of said circuits, means for energizing the remaining winding of each of said elements in accordance with the vector difference of said voltage conditions, the relative directions of said windings being such that the torques of said elements normally oppose, and means including said movable member for causing said switch to close when said voltage conditions are in a predetermined relationship of magnitude and phase position.
9. In apparatus responsive to the condition of synchronism of a pair of alternating-current circuits, a pair of induction elements each comprising a magnetic structure having a first magnetic pole included in a first magnetic path and a second magnetic pole positionally displaced from said first magnetic pole and included in a second magnetic path, winding means inductively associated with each of said magnetic structures and operable to produce time-displaced fluxes in the poles thereof in response to voltage conditions derived from said circuits, induction armature means subject to opposing forces produced by said elements, and means for adjusting the relative forces produced by said elements comprising means for varying the reluctance of one of said paths.
